UNITED STATES PATENT OFFICE.

JAMES J. NIVEN, OF PHILADELPHIA, PENNSYLVANIA.

EQUALIZING-VALVE.

1,142,117.

Specification of Letters Patent.

Patented June 8, 1915.

Application filed April 27, 1914. Serial No. 834,863.

To all whom it may concern:

Be it known that I, JAMES J. NIVEN, a citizen of the United States, residing at Philadelphia, in the county of Philadelphia and State of Pennsylvania, have invented 5 certain new and useful Improvements in Equalizing-Valves, of which the following is a specification.

My invention relates to improvements in 10 equalizing valves, the object of the invention being to provide a valve for equalizing the pressure in the sight glass of a low pressure steam boiler, so that the glass will accurately indicate the level of water in the boiler.

15 It is a well known fact that frequently there is an inequality in the pressure of the boiler and the sight glass, so that the glass does not properly record the level of water. This is due to the fact that there is an absence of air in the system. For example, 20 when the fire goes out, the system falls below atmospheric pressure and when the steam is generated, it will exert a pressure upon the liquid in the sight tube to force the latter 25 downwardly below the normal water level.

It is the purpose of my improved equalizing valve to overcome any such imperfect operation and to insure a perfect reading of the sight glass at all times.

30 With these and other objects in view, the invention consists in certain novel features of construction and combinations and arrangements of parts as will be more fully hereinafter described and pointed out in the 35 claims.

In the accompanying drawings: Figure 1 is a view in elevation illustrating my improved equalizing valve in connection with an ordinary type of steam boiler, such as 40 used for house heating and the like. Fig. 2 is an enlarged view in longitudinal section through my improved equalizing valve, and Fig. 3 is a view in transverse section on the line 3—3 of Fig. 2.

45 1 represents a steam boiler, 2 are steam pipes for conveying the steam to radiators in the building.

3 are branch pipes connected with the steam pipes 2, and with these branch pipes, 50 my improved equalizing valve 4 is connected by means of a T-coupling 5.

At one side of the boiler 1, a sight glass 6 is located and connected by pipes 7 and 8 with the boiler so as to permit a communication 55 with the latter and indicate in the glass tube, the level of water in the boiler.

My invention is not limited to any particular type of sight glass, and I preferably use any ordinary construction in common use. I have indicated on the upper tube 7, 60 a pressure gage 9, but this, of course, forms no part of my invention.

My improved equalizing valve comprises a cylindrical casing 10 having a screw-threaded nipple 11 at its lower end for engagement with the T-coupling 5, so as to support the valve casing in a vertical position.

12 is a plug which is screwed into the upper end of the valve casing, and is steam 70 and air tight. In the valve casing, I locate a hollow float 13 which is preferably of relatively thin metal conforming in shape to the shape of the cylinder, closed at its upper end as shown at 14, and open at its 75 lower end, so that its interior is open to communication with the system.

The casing 10 is provided with internally screw-threaded valve casings 15 in which ball valves 16 are located. Plugs 17 are 80 screwed into the valve casings and have curved valve seats 18 at their inner ends, and are provided with longitudinal air inlet passages 19. The balls 16 project through openings 20 in casing 10, and are 85 engaged by the float 13. The float has an annular curved portion 21 which constitutes a cam surface, so that the longitudinal movement of the float controls the position 90 of the balls. In Fig. 2, the movement is illustrated in a somewhat exaggerated form, and it is to be understood that a very slight movement of the float gives to the balls a sufficient movement to open and close the 95 passages 19. The cam portion 21 is so shaped that when the float falls, the balls can move away from the inner passages 19 and allow air to enter the casing around the outside of the float and pass downwardly 100 into the boiler. When the float is elevated, this cam portion moves the balls back and closes the air inlet ports. The balls are in constant engagement with the walls of the hollow float and are controlled by the movement of the float either to permit the balls 105 to open or to move them to closed position.

The operation is as follows: When the pressure in the boiler falls below normal, the float 13 will drop and the balls 16 will be moved away from the ends of passages 19, and air will be drawn into the boiler 110 through the passages 19, openings 20, and

around the outside of float 13. When the steam pressure rises, the steam will cause the float to move upwardly and at the same time will exert an internal pressure in the 5 float, so that while the balls are moved back to closed position, the float will also be expanded so that it snugly fits the inside of the casing and forms a steam tight joint.

The operation of the valve is entirely automatic and prevents any possibility of the 10 pressure decreasing to such a point as to cause the sight valve to open in anything but a correct manner. When my improved valve is in position, the pressure is always 15 equalized, so that the sight tube will always record the pressure level of water.

Various slight changes might be made 20 in the general form and arrangement of parts described without departing from my invention, and hence I do not limit myself to the precise details set forth, but consider myself at liberty to make such changes and alterations as fairly fall within the spirit and scope of the appended claims.

25 Having thus described my invention, what I claim as new and desire to secure by Letters Patent is:

1. An equalizing valve of the character described, comprising a casing constructed 30 at its lower end for attachment to a boiler, a hollow float in the casing having a closed upper end and an open lower end, and air inlet valves in the sides of the casing directly engaged by the float and controlled 35 by the movement of the float, substantially as described.

2. An equalizing valve of the character described, comprising a casing constructed at its lower end for attachment to a boiler,

a hollow float in the casing having a closed 40 upper end and an open lower end, air inlets in the sides of the casing, balls controlling said inlets, and said float directly engaging and adapted to move the balls, substantially as described.

3. An equalizing valve of the character described, comprising a casing constructed at its lower end for attachment to a boiler, a hollow float in the casing having a closed 45 upper end and an open lower end, valve casings on the sides of the first-mentioned casing having openings therein communicating with the interior of the first-mentioned casing, plugs screwed into the valve casings and having air passages there- 50 through, balls in said openings adapted to close the air passages, and said float having a surface adapted to contact with the balls and controlling the movement of the balls by the vertical movement of the float, sub- 55 substantially as described.

4. An equalizing valve of the character described, comprising a casing having a screw-threaded nipple at its lower end, a plug screwed into the upper end of the casing, a hollow float in the casing having a closed upper end, and an open lower end, and valves in the sides of the casing directly engaged by and controlled by the 60 float, substantially as described.

70 In testimony whereof I have signed my name to this specification in the presence of two subscribing witnesses.

JAMES J. NIVEN.
